UNITED STATES PATENT OFFICE

SIEGFRIED KAHN, OF ALBUQUERQUE, NEW MEXICO

MEMORANDUM PAD FOR DESK TELEPHONES

Application filed June 6, 1931. Serial No. 542,663.

This invention relates to a memorandum pad holder and advertising device for desk telephones.

5 A primary object of the invention is to so construct an attachment of this character that it may be quickly and easily applied to the telephone base and standard and which when applied will not in any way disfigure the instrument and yet be in position for 10 quick use when telephoning.

Another object of the invention is to so construct an attachment of this character that while affording a maximum amount of 15 writing space will yet be so light in weight as not to interfere in any way with the use of the telephone.

Another object of the invention is to so 20 construct a pad and its support that it may be positioned on the base and standard of the telephone instrument so that the party using the phone may have the receiver in his left hand and the pencil in his right over the pad ready for making memorandums of the 25 conversation.

In carrying out these objects, the invention 30 is susceptible of a wide range of modification without departing from the spirit or sacrificing any of the advantages of the claimed invention; there being shown in the drawing for illustrative purposes a preferred and practical form, in which:

Figure 1 is a perspective view showing a 35 telephone instrument equipped with this improved pad; and

Fig. 2 is a plan view of the pad detached;

In the embodiment illustrated, a desk telephone of usual construction is shown having the base B and standard S on which the 40 combined advertising device and pad holder 1 is designed to be mounted.

This attachment comprises a plate 2 composed of celluloid, card board or some similar light material shaped to conform to the shape 45 of the base B having a central opening 3 to encircle the standard S with an entrance slit 4 leading therefrom preferably at an oblique angle, said slit 4 terminating in a smaller opening 5 designed to surround the cord C in 50 which the conducting wires are housed. Leading from the opening 5 through the edge

of the plate 2 is another slit 6 which is preferably extended in a direction opposite to the slit 4 to insure the plate 2 having a firmer grip on the standard S.

One half, more or less of the plate 2 may be used for advertising and the portion here shown for this purpose is numbered 7 while the remainder thereof forms a support for a pad or calendar pad 8. This pad 8 may be of any desired form and has a central opening registering with the opening 3 of the plate 2 and it also has a slot 9 formed therein registering with the slit 4 in said plate. This pad may be secured to the plate 2 by any suitable means being here shown connected by staples 10 along the edge adjacent the advertising portion of the holder.

It will thus be seen that this attachment may be very cheaply manufactured and easily applied to and removed from a telephone instrument, and when applied will not interfere in any way with the use of the telephone which may be readily lifted from place to place as the pad weighs only about two 75 ounces.

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed.

I claim:

1. A pad holder for telephones comprising a plate having a standard encircling opening with an entrance slit leading from said opening through the edge of the plate.
2. A pad holder for telephones comprising a plate shaped to fit over the base of a telephone instrument and having a standard encircling opening with an entrance slit leading from said opening through the edge of the plate, said plate also having another opening intermediate the ends of the slit to receive the conductor cord.
3. A pad attachment for telephones comprising a plate having a standard encircling opening with an entrance slit leading from said opening through the edge of the plate,

and a pad attached to said plate and extending over a portion of the area thereof.

4. A pad attachment for telephones comprising a plate having a standard encircling opening with an entrance slit leading from said opening through the edge of the plate, and a pad attached to said plate and extending over a portion of the area thereof, said pad having an opening registering with the 10 standard opening of the plate and a slot extending from said opening through one side wall communicating with the slit in the plate to provide for the application of the attachment.
- 15 5. A pad holder for telephones comprising a plate having a standard encircling opening with an entrance slit leading from said opening thru the edge of the plate, a portion of the slit extending at an oblique angle 20 to said opening.

6. A pad holder for telephones comprising a plate shaped to fit the base of a telephone instrument having a standard encircling opening with an entrance slit extending from said opening and merging into another opening formed between the standard encircling opening and the edge of the plate, and another slit extending obliquely 25 from said second opening thru the edge of 30 the plate.
